TOY HELMET

Henry Orenstein, Verona, N.J., assignor to De Luxe
Reading Corp., Elizabeth, N.J., a corporation of New
Jersey

Filed Dec. 15, 1964, Ser. No. 83,047
Term of patent 3½ years

(Cl. D3—13)

FIG. 1

FIG. 2

FIG. 3

FIG. 4

FIG. 1 is a perspective view of a toy helmet embodying the present design;

FIG. 2 is a top view;

FIG. 3 is a side view;

FIG. 4 is a view from underneath;

FIG. 5 is a front view; and

FIG. 6 is a rear view.

The essential features of my new design reside in the full line disclosure on the drawing.

I claim:

The ornamental design for a toy helmet, substantially as shown and described.
